[57] CLAIM

The ornamental design for a slide track for a dispenser for cans or bottles, as shown.

DESCRIPTION

FIG. 1 is a perspective view of a slide track for a dispenser for cans or bottles showing our new design;

FIG. 2 is a top plan view thereof;

FIG. 3 is a side elevational view thereof;

FIG. 4 is a front elevational view thereof;

FIG. 5 is a rear elevational view thereof; and

FIG. 6 is an enlarged fragmentary cross-sectional view taken along line 6—6 of FIG. 2.

FIG. 1

FIG. 5

FIG. 2

FIG. 3

FIG. 6

FIG. 4
